Filed Oct. 15, 1965, Ser. No. 87,491

Term of patent 7 years

(Cl. D56—4)

Fig. 1

Fig. 2

Fig.3.Fig.4.

FIG. 1 is a front elevational view of a portable phonograph or similar article, showing my new design in playing position;

FIG. 2 is a side elevational view, in closed position, the opposite side being substantially a mirror image thereof;

FIG. 3 is a side elevational view in playing position, the record playing mechanism being omitted for convenience in illustration; and

FIG. 4 is a top plan view thereof, to a reduced scale. The dominant features of my new design are shown in solid lines in the drawings. The speaker grill fragmentarily shown is continuous within the boundaries indicated.

I claim:

The ornamental design for a portable phonograph or similar article, as shown and described.
